UNITED STATES PATENT OFFICE.

FRANK N. REEVES, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,252,948.

Specification of Letters Patent.

Patented Jan. 8, 1918.

Application filed November 13, 1916. Serial No. 131,044.

To all whom it may concern:

Be it known that I, FRANK N. REEVES, a citizen of the United States, residing at Newark, in the county of Essex and State 5 of New Jersey, have invented certain new and useful Improvements in Telephone-Exchange Systems, of which the following is a full, clear, concise, and exact description.

This invention relates to telephone 10 exchange systems and relates to allotters for determining the order in which certain pieces of apparatus shall be operated.

The object of this invention is the provision of means whereby an automatic 15 switch may be instantly allotted for service upon the seizure of a previously allotted switch.

Heretofore the allotment of a second switch has awaited the movement of the one 20 previously allotted (the allotter being under the control of the latter, whereby a certain amount of time was lost in placing the former in condition for service). In the present invention this loss of time is obvi- 25 ated by putting the allotter under control of the same means which controls the previously allotted switch, so that by the time this previously allotted switch has actually started to move, a new switch has been allotted.

In the drawings, Figure 1 represents dia- 30 grammatically a telephone substation and its associated central office apparatus, and Fig. 2 above the horizontal broken line re- 35 presents diagrammatically three panel type line finders, and below the broken line three relays and a sequence switch comprising the allotter are shown.

In the operation of a system in which this 40 improvement is employed, a group of lines are served by a number of line finders, of which one is allotted and ready to go into service, another is preselected for allotment, while others are in service, and still others 45 are idle. When a call is initiated, a common start wire is grounded, whereupon an 18-position sequence switch associated with the allotted switch is caused to move forward to start an idle switch in motion. The 50 movement of this sequence switch at the same time produces circuit changes in the allotter, which result in the advance of the preselected switch to the allotted position and the preselection of another idle switch.

The invention has been shown in connection with a part of a telephone system comprising a calling line, and three line finders available for extending a call. 55

It is thought that the invention will best be understood from the following detailed 60 description.

Referring now especially to Fig. 1, S represents a telephone substation, LR the line relay, and CO the cut-off relay associated therewith. Relay 1 and relay 2 are pro- 65 vided to serve the group of lines in which the calling line from substation S is included. Relay 3 is common to a number of groups of relays similar to 1 and 2.

When a call is initiated at the substation 70 S, through the removal of the receiver from its hook, a circuit is established from ground, battery, winding of line relay LR, inner armature and contact of cut-off relay CO to the upper limb of the line leading to the substation S, through the apparatus comprising the substation, back through the lower limb of the telephone line, outer contact and armature of cut-off relay CO to ground. 75 The armatures of line relay LR are thereby 80 attracted, whereupon a circuit is established from ground, left-hand armature and contact of relay LR to the contact and armature of relay 1, through the winding of relay 2, normal contacts of the right-hand 85 armature of relay 2, contact and left-hand armature of relay 3 to battery and thence to ground. Relay 2 is energized in this circuit and attracts its armatures. Thereupon a circuit is established from ground, 90 battery, through the winding of relay 3, through the left-hand alternate contact and armature of relay 2, the winding of relay 2, the armature and contact of relay 1 through the left-hand armature and contact of relay LR, to ground, whereby relay 95 2 is locked up and the relay 3 is energized.

The action of the relays associated with the substation S just described now results in the movement of a line finder. A circuit 100 is set up from ground, battery, winding of relay 3, alternate contact and left-hand armature of relay 2, alternate contact and right-hand armature of relay 2, conductor TW, to a trip magnet TM and thence to 105 ground. This trip magnet attracts its armature and rotates the common trip rod TR, serving all line finders connected with the

group of lines, in which the calling line is included. At the same time, a circuit is set up from ground, right-hand armature and contact of relay 3 to the common start 5 wire SW.

Assuming that position 1 of the sequence switch, such as sequence switch 100, serving a line finder is the allotted position and that line finder LF' is in this position. The 10 ground connected with the start wire SW is connected through sequence switch contact 101 to the winding of relay 120 to battery and thence to ground. Relay 120 attracts its armatures and a circuit is established from ground, right-hand armature and alternate contact of relay 120 through the sequence switch contact 102, the motor magnet of sequence switch 100 to battery and thence to ground. Sequence switch 100 15 moves under control of its contact A' into position 3.

Let us assume that line finder LF' is in a preselected position, in which case its sequence switch 200 will be found in position 25 16. As sequence switch 100 moves out of position 1 and passes through position 2, a circuit is established from ground, sequence switch contact 103 to the winding of relay 4 to battery and thence to ground. Relay 4 attracts its armature and establishes a locking circuit for itself from ground, battery, winding of relay 4, contact and left-hand armature of relay 4, normal contact and right-hand armature of relay 5 to 30 ground. Relay 4 in attracting its armatures establishes a circuit from ground, right-hand armature and contact of relay 4, sequence switch contact 51, sequence switch contact 205 to the motor magnet of sequence 35 switch 200, battery and thence to ground. Sequence switch 200 moves under control of its contact A' into position 1, and is thereby allotted for service with the next calling line.

45 As sequence switch 200 moves into position 16₁, a circuit is established from ground, battery, sequence switch contact 206, conductor 150, winding of relay 5 and thence to ground, whereupon relay 5 attracts its 50 armatures, thereby breaking the locking circuit of the relay 4 which retracts its armatures. Relay 5 establishes a locking circuit for itself from ground, battery, left-hand armature and contact of relay 6, left-hand 55 armature and contact of relay 5, through the winding of relay 5 to ground. Relay 5 also establishes a circuit from ground, right-hand armature and alternate contact of relay 5, right-hand armature and contact of relay 6, 60 motor magnet of sequence switch 50, battery, and thence to ground. Sequence switch 50 now rotates its contactors until stopped in its movement by the preselection of an idle switch.

65 Suppose now that line finder LF' is in

use, line finder LF' is allotted, and that line finder LF' is idle. In the idle position of line finder LF', the sequence switch 300 will be resting in position 14. Then, as sequence switch 50 begins to move, in passing into position 2₃, a circuit will be established from ground, sequence switch contact 303, sequence switch contact 52, winding of relay 6, contact and left-hand armature of relay 5, contact and left-hand armature of relay 6, to battery and thence to ground. Relay 6 is energized and attracts its armatures. Thereupon the locking circuit for relay 5 is broken and it retracts its armatures. This serves in turn to break, at the right-hand armature and alternate contact of relay 5 the energizing circuit for the motor magnet of sequence switch 50 which comes to rest in position 3. The allotter comprising the relays 4, 5 and 6 and the sequence switch 50 now rest in normal position.

It will be seen then that the grounding of the start wire SW has the effect of instantly allotting a new line finder for service, and preselecting another for allotment.

When sequence switch 100 reached position 3 a circuit was established from ground, the right-hand armature and alternate contact of relay 120, sequence switch contact 107, the up-drive magnet 121 to battery and thence to ground. Magnet 121 attracts its armature and thereby presses the driving ribbon DR' of the line finder LF' against the constantly rotating roller 122. As the line finder switch moves in an upward direction, the pawl P' engages the catch C' secured to the common trip rod TR and releases the brushes B¹, B², B³ and B⁴ in the well-known manner. As the sequence switch 100 passed out of position 1 into position 3 the relay 120 was maintained energized through a circuit from ground, battery, the winding of relay 120, the contact and left-hand armature of relay 120, sequence switch contacts 108 and 109 to the commutator segment CS', the brush B⁵ and thence to ground. In the upward movement of the line finder brush set, the brush B⁵ is arranged to pass over insulated segments in the commutator CS' as the brush B⁴ rests on terminals T⁴. Should the first terminal set thus encountered be not one of a calling line, a circuit will be established from ground, the left-hand winding of relay 1, the normal contact and armature of relay 120 LR to the terminal T⁴, the brush B⁴, the sequence switch contact 108 and thence through the circuit previously described to maintain the relay 120 energized while the brushes of line finder LF' pass over this set of contacts.

Relay 1 will be energized in this circuit and thereby open the holding circuit of relay 2. Relay 1 being slow to release will then hold its armature attracted until the

cut-off relay CO is energized as explained later. Relay 2 now retracts its armatures, resulting both in the deenergization of relay 3—whereby the ground is removed from the start wire SW and the release of the trip magnet TM.

When at last the terminals of the calling line are encountered, the test terminal T⁴ will be in a changed electrical condition, that is, battery will be connected thereto through the circuit from ground, battery, right-hand winding of relay 1, alternate contact and right-hand armature of relay LR to the terminal T⁴. Therefore relay 120 will be deenergized and the circuit for up-drive magnet 121 will be broken at the alternate contact and right-hand armature of relay 120.

The retraction of its armature by relay 120 establishes a circuit from ground, right-hand armature and normal contact of relay 120, the sequence switch contact 110 to the motor magnet of sequence switch 100 to battery and thence to ground. Sequence switch 100 moves under control of its contact A' into position 12.

When position 4 is reached by sequence switch 100, a circuit is established from ground, battery, resistance R', sequence switch contact 111, brush B², terminal T³, the winding of cut-off relay CO and thence to ground. The cut-off relay CO attracts its armatures, thereby breaking the energizing circuit for the line relay LR, which in turn retracts its armatures.

As sequence switch 100 continues in its movement toward position 12, the sequence switch contacts 112 and 113 are closed in position 10½ and remain closed until position 12 is reached where the sequence switch comes to rest. Thus the substation S is extended through the terminals T' and T², the brushes B' and B², the sequence switch contacts 112 and 113, through the windings of repeating coil RC' of the cord circuit connected with line finder LF'.

As position 10½ is passed, a current flow is established through the said circuit including the winding of supervisory relay 123, which is thereby energized. Supervisory relay 123, in attracting its armature, establishes a circuit from ground, armature and contact of relay 123, the winding of relay 120 to battery and thence to ground. Relay 120 attracts its armature and remains in this condition until the conversation over the telephone line is concluded, at which time the circuit just described is broken. Thereupon the return of the right-hand armature of relay 120 to its normal contact establishes a circuit from ground, through the armature and normal contact of relay 120, sequence switch contact 110, in the twelfth position, the winding of the motor magnet of sequence switch 100 to bat-

tery and thence to ground. Sequence switch 100 moves under control of its contact A' into its thirteenth position.

In position 13 sequence switch contact 114 is closed, thereby establishing a circuit for the down-drive magnet 124 from ground, battery, the winding of magnet 124, sequence switch contact 114 to ground. Magnet 124, in attracting its armature, presses the driving ribbon DR' against the constantly rotating roller 125, whereby the brushes B', B², B³ and B⁴ are returned to their normal position. As the normal position is reached, a circuit is established from ground, brush B⁶, commutator segment 126, sequence switch contact 115, motor magnet of sequence switch 100 to battery and thence to ground. Sequence switch 100 moves under control of its contact A' into position 14, where it remains idle until again preselected for allotment, as described in connection with line finder LF².

When another call is initiated start wire SW will be grounded, as before described, and in this case line finder LF² will go into service. Line finder LF² which was preselected will thereupon be advanced to the allotted position, and a new idle line finder such as LF' will now be preselected.

What is claimed is:

1. In a telephone exchange system, a group of telephone lines, a plurality of automatic switches in which said lines terminate for extending said lines, means individual to each switch for controlling said automatic switches, and an allotter for determining the order in which said switches shall be operated, said allotter comprising means for selecting a switch for service and means for preselecting a second switch for service, said allotter being controlled by the controlling means associated with the last of said switches to go into service.

2. In a telephone exchange system, a group of telephone lines, a plurality of automatic switches in which said lines terminate for extending said lines, means including sequence switches, one for each switch for controlling said automatic switches, means for selecting an idle automatic switch for allotment, and means for allotting a selected automatic switch for service in connection with the next line to be extended, said last mentioned means being controlled by the sequence switch associated with the last automatic switch to go into service.

3. In a telephone exchange system, a group of lines, a plurality of automatic switches in which said lines terminate for extending said lines, means including a sequence switch individual to each automatic switch for controlling said automatic switches, an allotter associated with said switches for determining the order in which they shall be operated, comprising means for selecting an

idle switch, and means for placing in readiness for operation a preselected switch, said last mentioned means being controlled by the sequence switch associated with the last 5 previously allotted switch.

4. In a telephone exchange system, a group of telephone lines, a plurality of automatic switches in which said lines terminate for extending said lines, means for controlling 10 said automatic switches including a sequence switch individual to each, and an allotter for determining the order in which said switches shall be operated comprising means for pre-selecting an idle switch, means for allotting 15 a preselected switch, said means being under control of the sequence switch associated with the last previously allotted automatic switch.

5. In a telephone exchange system, a group

of telephone lines, a plurality of automatic 20 switches in which said lines terminate for extending said lines, a controlling means for each of said automatic switches, and an allotter for selecting and preselecting said switches for service comprising means made 25 operative when a selected switch goes into service for advancing the pre-selected switch to the selected position, said means being under control of the means for controlling the last previously selected switch, and 30 means made operative when the preselected switch is advanced to the selected position for preselecting an idle switch.

In witness whereof I hereunto subscribe my name this 11th day of November, A. D. 35 1916.

FRANK N. REEVES.
